County, Mo., assignors to Day-Brite Lighting, Inc.,
St. Louis, Mo., a corporation of Missouri

Application April 11, 1958, Serial No. 50,447

Term of patent 14 years

(Cl. D48—23)

Fig. 1 is a top perspective view of a reflector for fluorescent lighting fixtures or the like, showing our new design;

Fig. 2 is a top plan view thereof;

Fig. 3 is a side elevational view thereof;

Fig. 4 is an end elevational view thereof; and

Fig. 5 is a sectional view taken on line 5—5 in Fig. 2.

The characteristic features of our design for the reflector disclosed reside in the longitudinal and transverse ribs on the central portion thereof having the configuration shown.

We claim:
The ornamental design for a reflector for fluorescent lighting fixtures or the like, substantially as shown and described.
